ROLL PAPER DISPENSING APPARATUS

Filed March 15, 1923

Fig. 1

Patented Oct. 6, 1925.

1,556,205

UNITED STATES PATENT OFFICE.

WILLIAM B. COLLINS, OF BEN AVON BOROUGH, PENNSYLVANIA.

ROLL-PAPER-DISPENSING APPARATUS.

Application filed March 15, 1923. Serial No. 625,315.

To all whom it may concern:

Be it known that I, WILLIAM B. COLLINS, a citizen of the United States, and residing in the borough of Ben Avon, in the county of Allegheny and State of Pennsylvania, have invented or discovered the new, useful, and Improved Roll-Paper-Dispensing Apparatus, of which the following is a specification.

My invention consists in new and useful improvements in means for dispensing paper, such as paper toweling, toilet paper, wrapping paper and the like, in measured quantities from a parent roll. It is much less expensive to put such paper up in a continuous roll as compared to supplying the same in cut and folded form, but previously dispensing such paper from a roll has been uneconomical, owing to the waste.

Dispensing apparatus has been made for this purpose in which the roll of paper is rotated to dispense the paper by a pull exerted on the loose end of the paper, and after the paper has been unrolled and detached the roll is rotated in the opposite direction to its former position. Means have been provided for limiting the dispensing rotation of the roll, and also for rotating the roll in the reverse direction.

The difficulty has been that the amount of paper delivered by a given rotation of the roll varies with the diameter of the roll of paper. Thus when a fresh roll is put in the dispensing apparatus a given rotation will deliver a much longer length of paper than is delivered when the roll of paper is materially depleted. It is therefore practically impossible to successfully dispense paper from such machines where the paper is characterized by transverse perforations at regular intervals, as such perforations are not presented at the proper position at the completion of each unwinding action.

The object which I have in view is the provision of practical means whereby substantially the same amount of paper will be unwound by each dispensing operation without material variation in length due to the varying diameter of the roll of paper. For the accomplishment of this purpose I have improved the roll paper dispensing apparatus by providing the same with means controlled by the amount of paper contained in the roll for regulating the rotation of the roll in the dispensing operation whereby substantially the same length of paper will

always be dispensed notwithstanding progressive depletion of the paper stored on the parent roll.

In the accompanying drawings wherein I illustrate an apparatus embodying the principles of my invention, Fig. 1 is a plan view of the same, the apparatus being in its position of rest; Fig. 2 is an end view looking from the left in Fig. 1, the apparatus being however in the position assumed when the paper has been unwound in a dispensing operation; Fig. 3 is a view similar to Fig. 2 but illustrating a modification, the apparatus being in its position of rest, and Fig. 4 is a detail view in cross section showing the paper core of the parent roll mounted on the spindle of the machine, taken along the line IV—IV in Fig. 1.

The following is a detailed description of the drawings.

A represents the support which may be a wall, a table or a board. B represents a fixed stand at one side and C the usual hinged stand at the other side of the support. D represents the axial spindle having one end fixed in the stand B while its other end is detachably secured to the stand C in such a manner as to hold said stand in its erect or extended position. Thus I have shown the spindle D provided with a spring finger 1 which snaps into engagement with a hook on the cylindrical boss 2 of the hinged stand C. The particular structure so far described forms no part of my present invention, and any other convenient manner of supporting the spindle in such a way that the parent roll may be slipped thereon may be adopted.

E is the metal mandrel upon which the roll of paper is mounted. Thus the mandrel may be a tube with a non-circular or flattened perimetral surface, or it may be an open frame. One end of the mandrel E, the left end in Fig. 1, is provided with a circular end plate 3, and near the other end of said mandrel is provided the filler plate 4. The plates 3 and 4 are axially perforated so that the mandrel E may be slid on to the spindle D, the plates 3 and the filler 4 being journaled on the spindle. Fixed axially to the outer surface of the end plate 3 is the spur gear F, the same being positioned inside the stand B. Meshing with said spur gear is a toothed quadrant G whose hub is journaled eccentrically of the parent roll as on a stud 5 projecting from the inside

of the stand B near the bottom thereof. Thus, when the mandrel E is rotated the quadrant G is swung on its axis.

H represents the paper in the form of a continuous roll wound about a paste-board or other core tube I of the proper internal form to slip easily over the mandrel E when the stand G is swung down to provide clearance. Thus the parent roll H, the mandrel 5 E and the pinion F will rotate in unison and their rotation will swing the quadrant G. In the drawings the rotation of the parent roll H in dispensing the paper is assumed to be clockwise, and thus the unwinding of the paper from the parent roll 10 will swing the quadrant G counterclockwise.

I provide means for returning the roll to its former position after the pull on the paper has ceased and the unwound paper is detached. Thus I may provide a spring 6 connecting the proper end of the quadrant to a fixed point on the support A. Thus the roll will be returned counterclockwise to 15 its position of rest. In Fig. 3 I have shown a weight 7 substituted for the spring 6; and it will be understood that any convenient means may be provided for accomplishing the return rotation of the roll. In Figs. 1 20 and 2 the parent roll is shown in the position which it assumed when the predetermined amount of paper has been unwound and before it has been returned into its original position. In Fig. 3 the roll is shown in the 25 position it assumes after having been rotated in the reverse direction.

The quadrant G is provided with a finger J which extends parallel with the axis of the paper roll, and which swings with the quadrant as the latter moves counterclockwise as the paper is unwound from the parent roll, until said finger comes in contact with the perimeter of the roll H as indicated in Fig. 2. It is evident that the contact of the 30 finger J with the parent roll will halt the rotation of the quadrant and thus halt the rotation of the parent roll thereby limiting the amount of paper which is unwound from said parent roll. It is also evident that as the parent roll diminishes in diameter the finger J will move farther in a counterclockwise direction, in the dispensing operation, thus permitting a greater rotation of the 35 parent roll. By this means I am able to compensate for the diminution of the parent roll, and by properly proportioning the parts, and the ratio of the pinion to the quadrant, so regulate the rotation of a parent roll so that substantially the same amount of paper will 40 always be delivered at an operation notwithstanding the variations of the diameter of the parent roll due to the removal of paper therefrom.

If it be desired to use a roll of unperfected paper any convenient form of cutting

mechanism may be provided, a number of which are well known in the art, but if paper transversely perforated at regular intervals is used my dispensing machine will deliver the perforations at the proper place 70 for detachment at each operation of the apparatus.

It is evident from the foregoing that paper toweling, toilet paper, wrapping paper and the like may be conveniently and economically dispensed by my device from a parent roll, a substantially uniform length of paper being delivered for detachment at 75 each operation of the apparatus, thereby insuring a uniformity in the sheets or lengths 80 detached.

Although, for the sake of clearness, I have described in detail the embodiment of the principles of my invention illustrated in the drawings, I do not wish to limit myself 85 thereby but claim broadly:—

1. In apparatus for dispensing sheets of paper of equal length from a parent roll, the combination of a support, a mandrel journaled in said support and rotating on a fixed axis, and upon which the roll of paper is mounted, a gear rigidly mounted on one end of said mandrel, a toothed sector rotatably mounted on said support and in mesh with said gear, and a finger extending from 90 said sector and brought into engagement with the perimeter of the roll by the unwinding movement whereby the length of paper unwound is governed by the diameter of the 95 roll of paper.

2. In apparatus for dispensing sheets of paper of equal length from a parent roll, the combination of a support, a mandrel journaled in said support and rotating on a fixed axis, and upon which the roll of paper is mounted, a gear rigidly mounted on one end of said mandrel, a toothed sector rotatably mounted on said support and in mesh with 100 said gear, a finger fixed on said sector and disposed at right angles to the plane of movement of said sector whereby said finger is brought into engagement with the perimeter of the roll to limit the extent of unwinding whereby the length of paper unwound is governed by the diameter of the 105 roll.

3. In apparatus for dispensing sheets of paper of equal length from a parent roll, the combination of a support, a mandrel journaled in said support and rotating on a fixed axis, and upon which the roll of paper is mounted, a gear rigidly mounted on one end of said mandrel, a toothed sector rotatably mounted on said support and in mesh with said gear, a finger extending from said sector and brought into engagement with the perimeter of the roll by the unwinding movement whereby the length of paper unwound is governed by the diameter of the roll of paper, and a spring actuated by said sector 110

to automatically return the sector and the roll of paper to their positions of rest when the pull is released from the paper.

4. In apparatus for dispensing sheets of paper of equal length from a parent roll, the combination of a support, a mandrel journaled in said support and rotating on a fixed axis, and upon which the roll of paper is mounted, a gear rigidly mounted on one end of said mandrel, a toothed sector rotatably mounted on said support and in mesh with said gear, a finger fixed on said sector and disposed at right angles to the

plane of movement of said sector whereby said finger is brought into engagement with the perimeter of the roll to limit the extent of unwinding whereby the length of paper unwound is governed by the diameter of the roll, and a spring connected to said sector to automatically return the sector and the roll of paper to their positions of rest when the pull is released from the paper.

Signed at Pittsburgh, Pa., this 10th day of March, 1923.

WILLIAM B. COLLINS.
